UNITED STATES PATENT OFFICE

JOSEPH GRALINSKI, OF NEW GALILEE, PENNSYLVANIA, ASSIGNOR OF ONE-FOURTH TO DAVID TRAMBATT, OF HILLIARDS, PENNSYLVANIA, AND ONE-TENTH TO ANDREW KADUNC, OF HILLIARDS, PENNSYLVANIA

SCREEN

Application filed June 20, 1929, Serial No. 372,475. Renewed October 6, 1931.

This invention relates to screens and is an improvement on my Patent No. 1,086,817, issued February 10, 1914.

The general object of the present invention is to provide a window screen that is not only movable with the window sash when the latter is opened and closed, but is easily and expeditiously removable from said sash whereby the window can be raised and lowered without the screen, so as to facilitate proper cleaning of the window glass and for other purposes.

A further object of the invention is to provide a window screen of the roller type, that includes a housing for the roller, for the protection thereof, the housing being provided with a slot to allow for the passage of the screen to and from the housing and extending from the side edges of the slot in a manner to allow free passage of the screen between the same are elastic strips to prevent the passage of dirt, dust and foreign matter within the housing as well as to prevent wear on the screen wire.

25 A further object of the invention is to provide a screen for windows, and of the character set forth, that is simple in construction, inexpensive to manufacture and install and extremely efficient in operation and service.

30 A still further object of the invention is to provide a window screen of the type referred to that can be easily and expeditiously applied and removed with respect to a window without making any changes whatsoever to the latter.

This invention also consists in certain other features of construction and in the combination and arrangement of the several parts, to be hereinafter fully described, illustrated in the accompanying drawings and specifically pointed out in the appended claim.

45 In describing my invention in detail, reference will be had to the accompanying drawings wherein like characters denote like or corresponding parts throughout the several views, and in which:

Figure 1 is a front elevation illustrating the application of my improved screen and showing parts in section.

50 Figure 2 is a sectional view taken approxi-

mately on line 2—2 of Figure 1 looking in the direction of the arrows.

Figure 3 is a sectional view taken approximately on line 3—3 of Figure 4.

Figure 4 is a vertical sectional view taken through the window and screen with the latter in rolled position and the window closed.

Referring to the drawings in detail, the letter A indicates a window frame, and B the lower sash which when raised and lowered moves the screen accordingly, and while I have disclosed the screen operated through the instrumentality of the lower sash, it will be obvious that my screens can be applied for operation by the upper sash. In this event two screens may be employed, one for each sash.

Secured to the confronting faces of the window frame and inwardly of the lower sash thereof are guide strips 1 that are of substantially U-shape in cross section with inwardly directed flanges 2 formed therewith as best shown in Figure 3. Mounted in the upper and lower ends of the guide strips are sprocket wheels 3 that have trained thereabout sprocket chains 4. The lower sprocket wheels are secured to the trunnions 5 of a spring pressed roller 6 that has fixed thereto in any well known manner and through the instrumentality of screws as shown in Figure 4, screen wire 7, the outer end of which is looped upon itself, as at 8, and extending through the looped end is a rod 9 which has its ends secured in one of the links of each of the sprocket chains as suggested in Figure 4.

Arranged on the inner sill and secured with respect thereto is a housing 10 that is provided with a substantially rounded forward wall merging in straight portions, while its rear wall is flat to conform to the shape of the lower rail of the lower sash. The housing is disposed about the roller and its screen as best shown in Figure 4, and formed in the upper wall or top of the housing is an elongated slot through which passes the screen. Secured to the top and extending longitudinally thereof upon opposite sides of the slot are elastic strips 11 that have their confronting faces spaced a sufficient distance apart to allow for the free passage of the screen, and

these elastic strips prevent the passage of dirt, dust and foreign matter within the housing as will be apparent.

Disposed in spaced parallelism and in equidistantly spaced relation with respect to each other are headed screws 12 secured to the lower rail of the lower sash adjacent its upper end thereof, and arranged whereby the heads are spaced a considerable distance from the rail. Carried by the lower rail is a hood 13 and for this purpose the hood is provided with a flanged upper edge 14 which is provided with openings of a size to pass freely over the heads of the screws, and the lower edge of the hood is likewise flanged as at 15 whereby it will lie flush with the sill and not damage the same as will be apparent. The hood is in reality secured to the screws 12 through the medium of a retaining strip 16 that has formed therein key hole shaped openings 17 for receiving the screws whereby the strip is held secured to said screws when the strip is positioned as shown in Figures 1 and 3 and when in this position, the heads 20 of the screws are arranged in the slotted ends of the key hole shaped openings, with the upper flange of the hood between the rail and the strip.

Secured to the ends of the retaining strip 30 16 are ears arranged in apertured pairs, and pivotally secured between each pair of ears is a pawl member 18 that is provided with a handle 19 to facilitate the easy operation thereof. These pawls are of a size whereby 35 the operating ends can be secured in the links of the sprocket chain 4 as shown in Figure 3. When the pawls are arranged in their last mentioned positions, it will be obvious that when the lower sash is raised and lowered, the screen will be moved accordingly, so that the screen will close the window opening when the window is raised.

The screws that secure the screen wire to the spring pressed roller pass through a strip 20 that may have one edge corrugated to fit in like corrugations arranged in the roller, and by this construction, it will be apparent that the screen wire is fixedly secured to the roller in a manner whereby casual separation of the wire therefrom is eliminated.

It is thought from the foregoing description that the advantages and novel features of my invention will be readily apparent.

55 I desire it to be understood that I may make changes in the construction and in the combination and arrangement of the several parts, provided that such changes fall within the scope of the appended claim.

60 What I claim is:

In a window screen device including a casing having a roller supporting a screen and sprocket chains connected to the roller and screen and carried by a window frame; 65 headed fasteners secured to a sash of the

frame, a hood having openings to receive the fasteners, said hood covering the casing when the sash is in window closing position, a plate having keyhole slots receiving the fasteners to secure the hood thereon, ears 70 formed on the ends of the plate, and dogs pivoted to the ears and adapted to engage certain links of the sprocket chains.

In testimony whereof I affix my signature.

JOSEPH GRALINSKI.
